WINDING DEVICE

William G. Knapp, Evanston, Ill., assignor to
Charles P. Peirce, Evanston, Ill.

Application December 8, 1943, Serial No. 513,341

7 Claims. (Cl. 179—100.2)

1

The present invention relates to a winding device, of a character adapted particularly for use in guiding wire in apparatus in which sound is adapted to be magnetically impressed on the wire as it passes through a suitable magnet box disposed between the wire supply and take-up spools.

In the present day systems of recording sound on wire, wire of very small diameters are utilized, and in the known apparatus provided for guiding the wire from the supply spool to the take-up spool, and vice versa, setting and breakage of the wire frequently occurs. In winding apparatus with which I am familiar traversing mechanisms are provided for guiding the wire upon the supply and take-up spools to and fro thereof in the direction of the axes of rotation of the spools in order to wind the wire in successive layers upon the spools. One of the chief difficulties with the prior art devices is that they incorporate unsatisfactory guide means for guiding the wire as it leaves and approaches the spools, in that they are of a character which cause the wire to set or break. These guide elements usually are in the form of a hook shaped loop and are disadvantageous in that in their guiding action they impart sharp turns which tend to set the wire resulting in easy fracturing of the same.

It is an object of my invention to provide a winding mechanism for guiding wire from a supply spool to a take-up spool or vice versa in which the wire is not subject to being set, eliminating the cause of frequent breakage of the wire.

In order to achieve the above noted object, I propose to provide a guide mechanism adapted to be carried or disposed intermediate a wire supply spool and a take-up spool which comprises a pivotally mounted plate member. The plate member has rotatably mounted thereon a pair of guide pulleys of a diameter so that when the wire is guided thereover a permanent deformation or set will not be imparted to the wire.

Suitable traversing mechanism is associated with the plate member so that the wire as it is passing from the supply spool to the take-up spool, or vice versa, is caused to be set upon a spool in successive abutting turns to and fro axially of the axis of rotation of the spools and in successive layers thereon.

In the preferred form of my invention the magnetic recorder, which may constitute either a recording mechanism and a transcribing mechanism, or both, is carried centrally of the plate member. The supply spool and the take-up spool are mounted for rotation in any suitable manner and disposed a sufficient distance apart to accom-

2

modate the plate member and the guide pulleys therebetween to provide for guiding the wire in relatively long sweeps between the pair of spools avoiding imparting of sharp turns or bends to the wire in its travel.

Suitable drive mechanism is incorporated with the winding device, and the drive mechanism is of a character providing for feeding the wire at the appropriate speed through the magnet box 10 when the wire is passing from the supply spool to the take-up spool and through the recorder for recording sound thereon. The drive mechanism incorporates the feature of providing for a much higher speed of rewinding of the wire after 15 a recording has been made thereon i. e. when the wire is to be transferred from the take-up spool to the original supply spool to be in the position for passing through a transcriber for transcribing the sound recorded on the wire.

Now, in order to acquaint those skilled in the art with the manner of constructing and operating a winding device in accordance with my invention, I shall describe in conjunction with the accompanying drawings a preferred embodiment of 20 the same.

In the drawings:

Figure 1 is a front elevational view of the upper part of a winding device constructed in accordance with my invention;

30 Figure 2 is a rear elevational view of the winding device of my invention;

Figure 3 is a plan view of the device shown in Figures 1 and 2;

Figure 4 is a detail vertical sectional view taken substantially on the line 4—4 of Figure 3; and

35 Figure 5 is a detail vertical sectional view on an enlarged scale and taken substantially on the line 5—5 of Figure 3 looking in the direction indicated by the arrows, with certain of the parts being shown in elevation.

Referring now to Figures 1 and 2 it will be seen that the winding device comprises a supporting frame 1 having a vertically extending panel portion 2, a horizontally extending base portion 3 providing for support of the device in the position shown in Figures 1 and 2. The vertical side edge portions of panel 2 are bent rearwardly to provide side flanges 4—4 and the upper edge portion of panel 2 is also bent rearwardly to provide a flange 6. The side edge portions of the base panel 3 are turned upwardly to form flanges 7—7 and suitable reinforcing bar members 8—8 are secured at one of the ends thereof to the side flanges 4—4 of the vertical panel 2 40 with their other ends secured adjacent the outer

ends of the side flanges 7-7 of the base panel 3. A pair of vertically extending panels 9 and 10 for supporting the drive mechanism rearwardly of the upper end of panel 2 of the device herein disclosed, are secured in fixed spaced apart parallel relation by a plurality of studs 11, arranged with their opposite ends suitably secured along the several edges of the panels 9 and 10. The assembled plate members 9 and 10 are adapted to be supported in juxtaposition of the rear surface of the panel 2 of the supporting frame by means of a plurality of bolts 13 which extend through the panel 2 and have threaded engagement with the panel 9 at the corners and upper edge thereof. Suitable spacing washers 14 are disposed about the bolts 13 between the rear surface of the panel portion 2 of the frame and the front surface of the panel 9 to space the latter away from the rear surface of the vertically extending panel 2 of the supporting frame 1. In the arrangement shown in the drawings, a wire supply spool 15 is mounted for rotation about a horizontal axis upon a shaft 16 which extends through the panel members 2, 9 and 10 at the upper end of the device adjacent the left hand side thereof as viewed in Figures 1 and 3. Suitable bearings 17 are associated with the panels 9 and 10 and the shaft 16 to provide a bearing mounting for the shaft. The shaft 16 at the end thereof forwardly of the front face of the vertical panel 2 is provided with a pivotally mounted spring pressed finger 18 which together with a stop collar 19, fixed to the adjacent end of the shaft, provide for mounting of the spool 15 for rotation with the shaft 16. A driving pulley 21 is fixed to the opposite end of the shaft 16.

A wire take-up spool 23 is mounted for rotation about a horizontal axis upon a shaft 24 extending horizontally through the panels 2, 9 and 10, at the upper end of the device adjacent the right hand side thereof as viewed in Figures 1 and 3. The shaft 24 is assembled for rotation in bearings 17 in the same manner as that described in conjunction with the shaft 16 for the supply spool 15 and the parts bearing like reference numerals to the parts previously described in connection with the take-up pulley 15 are identical. The shaft 24 has keyed thereto a suitable worm 25 intermediate the panels 9 and 10 for rotation with the shaft. A driving pulley 27 is keyed to the rear end of the shaft, and, as shown, is of greater diameter than the pulley 21 keyed to shaft 16.

A plate member 30 is disposed intermediate the spools 15 and 23 in a position to lie forwardly of the front surface of the vertical panel 2 of the supporting frame. A pair of substantially L-shaped brackets 31, as viewed in plan, are secured to the vertical panel 2 with a leg portion extending in a direction away from the front face of panel 2. The bearing plate 30 is provided adjacent its side edges intermediate the upper and lower edges thereof with bearing block members 33. A pivot pin 34 extends through and is secured in the outwardly extending leg of each of the bracket members 31 into the bearing blocks 33 to mount the plate member 30 for pivotal movement about a substantially horizontally extending axis. It will be observed from the several figures that the axis of rotation of the take-up spool 23, the supplying spool 15 and the axis defined by the pivotal mounting of the plate member 30 all lie substantially in a common horizontal plane.

An idler guide pulley 35 is mounted for rotation in the plate member 30 adjacent the upper right hand corner thereof as viewed in Figure 1. The

guide pulley 35 is mounted for rotation about a suitable bolt 36, and the pulley is spaced from the forward surface of plate 30 by a spacing collar 37 and the enlarged annular flange portion 38 of a threaded sleeve member carried by the plate member 30 and with which the bolt 36 has threaded engagement. A second idler guide pulley 40 is mounted for rotation at the lower left hand end of the plate member 30, as viewed in Figure 1. The pulley 40 is mounted for rotation in the plate member 30 in the same manner as the guide pulley 35 and the like reference numerals in describing the mounting of the latter pulley described identical parts for the pulley 40. A magnet box 41 is suitably secured centrally of the plate member 30. The structure of the magnet box is conventional and is provided with a cable 42 containing the electrical leads therefor. It will be understood that so far as the structure of my present invention is concerned that the magnet box 41 may be of the character for recording sound upon wire, or of a character for transcribing sound which has been recorded on wire, or both. The supply spool 15, take-up spool 23 and the guide pulleys 35 and 40, together with the plate member 30 are preferably arranged and constructed in the proportions shown in the several figures so that the wire indicated at W from the supply spool is adapted to be threaded over the pulley 35, thence through magnet box 41, thence over the pulley 40 to the take-up spool 23. In this manner a relatively long sweep of wire is provided to extend between the supply spool 15 and the guide pulley 35, and between the guide pulley 40 and the take-up spool 23. In a machine constructed in accordance with this disclosure, the supply and take-up spools were approximately 3 inches in diameter and the guide pulleys were approximately 1 3/4 inches in diameter. The pivotal axis of the plate member 30 is arranged so that it lies in a substantially horizontal plane extending through the axes of rotation of the supply and take-up spools, which are disposed to either side of the pivotal axis of the plate member 30. The diameter of the take-up and supply spools and guide pulleys 35 and 40 are sufficient to enable the wire to be trained thereover without distorting or setting the wire.

An electric motor 43 is suitably secured to the base panel 3 and a pulley 44 keyed to the end of the armature shaft. A belt 45 extends from the pulley 44 to a pulley 46 disposed centrally of the panel 10 adjacent the upper end thereof, and it is mounted for rotation about a shaft 47 carried in a block member 48. A shaft 49 extends transversely of panels 9 and 10 and extends through the upper end of the block member 48. Opposite ends of the shaft 49 are suitably secured in the panels 9 and 10 so that upon shifting of the block 48 about shaft 49 as an axis the friction hub portion 50 of the pulley 46 may be brought into engagement with either of a pair of pulleys 51 and 52. The pulleys 51 and 52 are suitably mounted for rotation about shafts secured in the panel 10. The belt 55 drivingly connects the pulley 51 with the pulley 21 carried by the shaft 16. A belt 56 provides a driving connection between the pulley 52 and the pulley wheel 27 secured to shaft 24. The panel 10 is provided with a slot 57 accommodating adjustment of the block member 48 so that the friction hub portion 50 of the pulley wheel 46 may be brought into engagement with the outer peripheries of either of the pulley wheels 51 and 52, selectively, to drive

either the supply spool or the take-up spool from the electric motor 43.

Reference may now be had to Figures 3, 4 and 5 for a description of the drive mechanism for causing pivotal movement of the plate member 30 about its axis providing a traversing mechanism for guiding the wire W from one spool to another. A worm gear 58 is suitably keyed on a vertically extending shaft 59, the opposite ends of which are mounted for rotation in lugs 60 of a vertically extending bracket 61 secured to the rear face of the panel 2 in position to provide engagement of the worm gear 58 with the worm 25 keyed to the shaft 24. The shaft 59 adjacent its lower end has a bevel gear 62 keyed thereto which bevel gear is adapted to have engagement with a bevel gear 63 fixed at one end to a horizontally extending shaft 64 which is mounted for rotation in a suitably horizontally extending bracket 65 fixed to the rear face of panel 9. At its other end the shaft 64 has suitably secured thereto a bevel gear 67 and this bevel gear has engagement with a bevel gear 68 carried by a shaft member 69. The shaft 69 is mounted for rotation about a horizontal axis and its opposite ends are suitably disposed in bearings provided therefor and carried by the panels 9 and 10. The shaft 69 is provided with double screw 70 upon which a nut 71 is adapted to be reciprocated axially of the shaft 69 upon rotation of the latter. The nut member 71 is provided with an upwardly extending yoke portion 72 having guiding engagement with a stud 73 secured at its opposite ends in the panels 9 and 10. The yoke portion 72 of the nut member 71 and the stud 73 provide for guiding movement of the nut member axially of the shaft 69 and prevents rotation of the nut member. A cap member 74 is pivotally mounted about a horizontal axis on the lower end of the nut member 71 to which is secured a shaft 75. The other end of the shaft 75 has pivotal connection to a bearing block 76 fixed adjacent the lower edge of the plate member 30 intermediate its side edges.

The operation of the device is as follows: Assuming that the block member 48 is shifted to the right as viewed in Figure 3, the motor 43 will cause the pulley 52 to be driven which by virtue of the connection between it and the pulley 27 by the belt 56 causes rotation of the take-up spool 23. The worm 25 keyed to the shaft 24 through its meshing engagement with the worm gear wheel 58 rotates shaft 59 causing the bevel gear 62 to rotate the shaft 64 through the bevel gear carried at its end having meshing engagement with the bevel gear 62 of the vertical shaft 59. Rotation of the shaft 64 in turn through meshing engagement of the bevel gear 67 with the bevel gear 68 carried by the shaft 69 causes reciprocating movement of the nut member 71 on the shaft 69. This motion is transmitted by the shaft 75 by virtue of its connection with the cap member 74 and the bearing block 76 secured to the plate member 30 to cause the latter to pivot about its horizontal axis guiding the wire upon the take-up spool 23 after it has passed through the magnet box 41 to wind the wire upon the take-up spool 23. After the recording has been made and it is desired to rewind the wire upon the supply spool 15, the block member 48 is shifted to the left as viewed in Figure 3 to engage the friction drive hub portion 59 of the pulley 46 with the pulley wheel 51 causing the pulley wheel 21 to be rotated by virtue of the belt 55 connecting the pulley 51 and the pulley 21. Upon drive being imparted in the reverse direction to the supply spool 15 i. e., re-

verse to its direction of rotation when the wire is being taken off thereof for purposes of recording, the wire W is caused to move in a direction from the take-up spool to the supply spool reversing the direction of rotation of the spools 15 and 23, and idle pulleys 35 and 40 in which position the wire is now ready to be transcribed, or removed from the apparatus, or stored, or sent elsewhere for transcription purposes. When the parts are in the position last referred to, the wire upon being drawn off of the take-up spool 23 causes rotation of shaft 24 which in turn actuates the traversing mechanism for guiding the wire upon the supply spool.

In a device actually constructed in accordance with the embodiment of the invention herein disclosed, the several bevel gears, together with the double threaded screw of shaft 69 were designed to provide a gear reduction of 200 to 1 to provide one movement of the plate member 30 to 200 revolutions of shaft 24. The take-up spool 23 being approximately 1" wide thus provides for 200 turns of wire on this spool when wire of about .004 inch in diameter is used. The bevel pulley wheels are designed so that upon reverse movement of the wire W, i. e., from the take-up spool back to the supply spool, the diameters of the several pulleys and the like were designed to provide a ratio of 2 to 1 in order to provide for rapid rewinding of the wire upon the supply spool. This mode of operation is advantageous in that during the recording operation a predetermined and relatively slow speed of the wire through the magnet box is required to properly record the sound and in the rewinding of the recorded wire it is desirable to be able to do so rapidly in a minimum amount of time.

It is to be observed that by virtue of the construction above set forth that the take-up spool and supply spool as well as the idler guide pulleys 35 and 40 carried by the pivotally mounted plate 30, are all of relatively large diameter so that as the wire W is passed thereover, it will not be caused to take a permanent set. Further that the relatively long sweeps of wire extending from both spools to the idler pulleys of the plate member, and the absence of any mechanism for causing the wire to pass over a sharp corner effectively prevents setting of the wire so that there is little likelihood of breakage or distortion of the wire.

While I have shown what I consider to be the preferred embodiment of my invention, it will be understood that various modifications and rearrangements may be made therein without departing from the spirit and scope of the invention.

I claim:

1. In a device of the class described, the combination of a pair of spools spaced apart and mounted for rotation about parallel axes, a magnet box between said pair of spools and fixed against movement in a plane transverse of the axes of said spools, oscillating guide means for guiding wire from one spool to the other and through said magnet box, said guide means including means operative to maintain said wire in a fixed definite path for passage through said magnet box regardless of the amount of wire on either of said spools, and means for oscillating said guide means.

2. In a device having a magnet box through which a recording wire is adapted to be passed from one spool to another spool, and in which the spools are mounted for rotation about spaced parallel axes, the combination of a guide means

comprising a guide plate member mounted for pivotal movement about an axis extending at right angles to the axes of said spools, an idler guide pulleys rotatably mounted in said guide plate on axes transverse to the pivotal axis of the latter, said magnet box being fixed to said guide plate in juxtaposition of its pivotal axis, and means for oscillating said guide plate about its pivotal axis.

3. In a device of the class described having a wire supply spool and a take-up spool mounted for rotation about fixed spaced parallel axes, the combination of a guide means comprising a guide plate member mounted for pivotal movement about an axis extending substantially at right angles to the axes of said spools, and a pair of idler pulleys rotatably mounted in said guide plate about axes extending transversely of the pivotal axis of the latter, said pivotal axis of said guide plate and the axes of rotation of said spools lying in a common plane with the axis of said idler pulleys lying to either side of said pivotal axis of said guide plate, and means for oscillating said guide plate about its pivotal axis.

4. In a device of the class described the combination of a supporting frame, a first shaft rotatably mounted in said frame, a supply spool carried by said shaft for rotation therewith, a second shaft rotatably mounted in said frame and spaced from and extending substantially parallel to said first shaft, a take-up spool carried by said second shaft for rotation therewith, a guide means for guiding wire or the like from one spool to the other spool comprising, a plate member pivotally mounted about an axis extending at right angles to the axes of rotation of said shafts, a pair of idler guide pulleys about which the wire is adapted to be trained in passing from one spool to the other spool, said idler guide pulleys being mounted for rotation about axes transverse to

5

the pivotal axis of said plate member and to either side thereof, means for selectively driving either of said shafts, and means interconnecting said plate member and said second shaft adapted upon rotation of the latter to oscillate said plate member about its pivotal axis.

10

5. The combination of claim 4 in which the means for selectively driving the shafts comprises a first pulley keyed to the first shaft and a second pulley keyed to the second shaft, said first pulley being of smaller diameter than said second pulley.

15

6. In a device of the class described, the combination of a pair of spaced apart spools mounted for rotation about parallel axes, a magnet box between said pair of spools fixed against movement in a plane extending transversely of the axes of said spools, oscillating guide means for guiding wire from one spool to the other spool axially to and fro on said spools through said magnet box, said guide means including means between each of said spools and said magnet box adapted to maintain said wire in a fixed definite path for passage through said magnet box, and means for oscillating said guide means.

20

7. In a device of the class described, the combination of a pair of spaced apart spools mounted for rotation about parallel axes, a magnet box between said pair of spools fixed against movement in a plane extending transversely of the axes of said spools, oscillating guide means for guiding wire from one spool to the other spool axially to and fro on said spools and through said magnet box, said guide means including means for guiding wire to and from the spools through said magnet box in a direction opposite the normal direction of movement of the wire from one spool to the other spool, and means for oscillating said guide means.
